UNITED STATES PATENT OFFICE.

EUGENE G. HANFORD, OF WESTFIELD, NEW JERSEY.

DESIGN FOR A TROUSERS-HANGER.

SPECIFICATION forming part of Design No. 26,280, dated November 17, 1896.

Application filed October 3, 1896. Serial No. 607,802. Term of patent 7 years.

To all whom it may concern:

Be it known that I, EUGENE G. HANFORD, a citizen of the United States, residing at Westfield, county of Union, State of New Jersey, 5 have invented and produced a new and original Design for Trouzers-Hangers, of which the following is a specification, reference being had to the accompanying drawings, showing a part thereof.

10 Figure 1 is a front view, and Fig. 2 a side view, of the trousers-hanger designed by me.

The head of the hanger is in the form of a closed triangle *a*. At the other end of the hanger is a closed ring *b*. Connecting the

head and ring and forming the body or shank 15 of the hanger is a flattened and widened portion *c*. The whole being made of one piece of metal forms a neat and attractive article for the purpose mentioned.

What I claim is—

20 The design for a trousers-hanger substantially as herein set forth and shown in the accompanying drawings.

E. G. HANFORD.
